UNITED STATES PATENT OFFICE.

GABRIEL ABRAHAM, OF NEW YORK, N. Y.

GARTER.

Application filed April 7, 1927. Serial No. 181,624.

This invention relates to garment supporters of the general type known as garters, sleeve holders, or the like, and has particular reference to a device of the character indicated that is calculated for the longest period of usefulness without breakage or destructive deterioration.

Among the objects of the invention is to provide a garter, the main circumferential band of which is of the utmost flexibility but preferably devoid of elasticity, being in the nature of non-elastic tape and hence of a practically indestructible composition.

Another object of the invention is to provide in or in connection with the triangle or pad portion of the garter spring means preferably of a metallic nature for affording the desired and important elasticity that should be inherent in an article of this character, the spring means being so constructed and arranged as to be well protected from the person of the wearer and for its own protection so that the spring mechanism will be practically indestructible, thereby adding to the length of life of the garter as a whole.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings in which like reference characters designate the same parts in the several views, and in which—

Figure 1 is a front elevation of a preferred embodiment of my invention, slightly broken away to disclose the mechanism.

Fig. 2 is a diagram showing the spring and plate mechanism.

Fig. 3 is a longitudinal sectional detail on the line 3—3 of Fig. 1, and on about the same scale as Fig. 2.

Referring now more particularly to the drawings I show my invention as embodied in the form of a garter such as is commonly worn by men for supporting their socks, and comprising a pad portion 10 which may be spoken of as of generally triangular form but with the points cut off and composed of a plurality of plies of material of leather or other tough strong durable material and comprising as shown a face panel 10^a and a back panel 10^b which except as soon to be

noted are stitched together all around their periphery as shown at 11. The face panel 10^a is provided with a slot 12 extending along a line from approximately the center of the diagonal toward one end of the triangle, the end corresponding to the opening of the garter. This slot may be formed or finished in any suitable manner to increase its strength and durability.

Within the lower angle portion of the triangle or pad 10 is secured between the panels thereof a sock attachment tab 13 of any suitable or conventional construction.

A band 14 of flexible and preferably non-elastic material in the nature of tape is attached at one end at 15 between the plies of the pad and secured in such position by the stitching aforesaid or otherwise as may be deemed best. The other end of the band 14 is connected by means of an adjustment 7^a buckle of any suitable nature 16 to a loop 17 usually formed of metal or its equivalent and for the usual purpose of fastening the band around the leg.

The principal feature of my improvement resides in the secluded metallic spring mechanism for the attachment of the loop 17. This mechanism comprises a plate 18 having formed or secured on one end of the front surface a button or head 19, and on the opposite side of the other end, a roll 20. This plate is made preferably of sheet metal or its equivalent and is substantially stiff. Secured to and within the roll 20 is one end or leg portion of a metallic compression spring 21, the same being shown as consisting of a succession of five or six legs, each two adjacent legs being connected by a coil 22 for maximum flexibility, providing thereby for the employment of spring material of considerable stiffness and strength. The end of the spring already mentioned is soldered or otherwise secured permanently and rigidly in or to the roll 20 of the plate, and the spring thence extends along the back surface of the plate and substantially beyond it, terminating in a leg 21^a that is slightly convexed in a direction away from the plate and which is adapted to lie within the end of the pad 10 remote from where the band 14 is attached at 15, in the nature of a pocket whereby it is held from movement up or down with respect to the pad. Before the plies of the pad are attached finally together, the spring mechanism is slipped into

place between the plies and the head 19 is projected outward through the slot 12. No other means is employed for holding the spring mechanism in the position indicated 5 and where it is kept in practice. The head acting as a button in or through the slot 12 prevents the slipping of the spring mechanism toward the opposite end of the triangle and so the head 19 is always in place to receive the loop 17 when the garter is applied 10 to the leg. The adjustment at the buckle 16 is of course an individual one according to the diameter of the leg and is made in accordance with the desired tension to be borne 15 by the spring 21. That is to say, when the garter is put on and the loop end 17 passed around the leg it is brought into the usual engagement with the head 19 which puts immediately the spring under a certain 20 amount of tension as indicated in Figs. 2 and 3, the end 21^a of the spring of course bearing against the end seam of the pad 10 as an abutment. The structure of the slot 12 is sufficient in firmness to cause the 25 spring mechanism to be drawn directly toward the abutment position with practically no lateral deviation. Any stretch or variation in effective length of the band will of course be taken care of as may be necessary 30 from time to time by the adjustment of the buckle 16. No practical deviation in the efficacy of the spring mechanism is incident to long usage or wear of the garter. The 35 direction of the axis of the slot 12 will of course be made in any event in accordance with the resultant of the three strains brought on the three corner portions of the pad 10, one of which is downward toward the sock.

I claim:

1. A garment supporter as set forth comprising a pad composed of a plurality of plies fastened together all round their periphery and spaced from each other within the central portion, the front portion of the pad being provided with an opening, a band fastened at one end of the pad, an attachment loop connected to the other end of the band, and metallic spring mechanism carried within the pad and comprising two principal parts,—a plate and a compression spring, one end of the spring having abutment relation with the end of the pad remote from where the band is attached, the plate being held by the spring spaced from the abutment point and having a head projected outward through said opening for co-operation with the attachment means carried by the band. 40

2. The herein described garment supporter comprising a pad of flat hollow construction, a flat wire expansion spring housed within the pad, one end of the spring abutting against the structure of one end of the pad, a flat plate attached to the opposite end of the spring and having a projection extending outward from the pad, a band attached at one end to the end of the pad remote from the point of contact with the spring aforesaid, and a member carried by the opposite end of the band for co-operation with said projection and whereby when the spring is put under compression the plate and projection are moved toward the 55 point of abutment. 60

In testimony whereof I affix my signature.

GABRIEL ABRAHAM.
